United States Patent Office.

SAMUEL M. FULTON AND WILLIAM M. FULTON, OF PITTSBURG, PENNSYLVANIA.

Letters Patent No. 97,383, dated November 30, 1869.

IMPROVED ROTARY BELL-HEAD.

The Schedule referred to in these Letters Patent and making part of the same

To all whom it may concern:

Be it known that we, SAMUEL M. FULTON and WILLIAM M. FULTON, of the city of Pittsburg, in the county of Allegheny, and State of Pennsylvania, have invented a new and useful Improvement in Rotary Bell-Heads; and we do hereby declare the following to be a full, clear, and exact description thereof, reference being had to the accompanying drawing, forming part of this specification, in which—

Figure 1 is a side elevation of a bell, furnished and hung with an improved bell-head.

Figure 2 is a front elevation thereof.

Figure 3 is a horizontal section of the bell-crown, in the line *o r* of fig. 1.

Figure 4 is a vertical section, through the crown and yoke, in the line *m n* of fig. 1.

In the several figures like letters of reference denote similar parts.

Our invention is designed, not only to remedy certain defects in the hanging of bells, but also to give a broad bearing for the crown of the bell, against the under side of the yoke, without entering it at all, and at the same time, to afford a more simple and ready mode of rotating the bell when it is desired to do so, and consists in the construction of an annular flanged cavity, in the crown-piece of the bell, around the central hole, for the clapper-bolt, for the reception of the heads of the bolts, by which the crown of the bell is attached to the yoke.

To enable others skilled in the art to construct and use our improvement, we will describe the construction and operation of our bell-head.

In the drawing—

A is the bell, attached to the yoke *E* by our improved device, and swinging on the trunnions *t* of the yoke, in the stands *B B*, which are bolted in the usual way to the frame *C*.

F is the bell-wheel, attached to one of the trunnions, *t*, of the yoke, for ringing the bell.

The yoke *E* is made in the usual way, excepting that it has not any hole for the reception of the crown-piece of the bell, which is usual in devices for rotating bell-heads, but only holes for the passage of the main or clapper-bolt *x*, and of the auxiliary bolts *a a'* *a'' a'''*.

The crown of the bell, which is the projecting portion situate centrally on top of the bell, by which it is attached to the yoke *E*, is cast with the bell, and consists of two parts, the central or inner part *w*, which surrounds the clapper-bolt *x*, and outer part *s*, which is concentric with the inner part *w*.

The outer part *s* may be made with the exterior shape of a frustum of a cone inverted, so as to give

a broader bearing against the under surface of the yoke *E*.

The inner part, *w*, of the crown, has a circular disk, *u*, on top, forming a projecting ledge all around it, and the outer part *s* is an annulus or ring *v*, projecting over its legs or sides, *s'*, toward and on a level with the disk of the inner part.

By this construction, there is formed in the crown of the bell a cavity, with an annular opening narrower than the cavity, the projecting of the ring *v* of the outer part, and of the disk *u* of the inner part, contracting the cavity in the crown, and forming ledges, under which rest the heads of the T-headed auxiliary bolts *a*, *a'*, *a''*, and *a'''*, by which the bell is attached to the yoke, in combination with the main or clapper-bolt *x*.

By the use of T-headed bolts, the heads projecting from two opposite sides and not all around the shank of the bolts, the head of each such bolt may be inserted between the disk *u* and ring *v* of the crown, into the cavity, when, being turned one quarter round, the head of the bolt rests under the flanges formed by the disk and ring, and thus sustains the bell, the bolts being passed upward through the yoke *E*, and secured by nuts screwed on the bolts.

Although we have described the crown of the bell as formed of separate pieces, inner and outer, and of legs *s*, disk *u*, and ring *v*, yet these parts are all cast together with the bell, and really form one piece with it.

Also, the outer piece *s* of the crown, instead of having legs *s'*, with spaces between them, may be in one piece, without such spaces; but it is sufficiently strong, and more easily cast when made as shown in the drawing, and more particularly in detail in figs. 3 and 4.

The clapper of the bell is attached in any desired way, to the lower end of the main or clapper-bolt *x*, which passes up through the centre of the bell-head, and, of course, through the centre of the crown-piece *w*.

It also passes up through a slotted hole in the yoke *E*.

This slot in the bolt-hole of the yoke *E* is made to receive a pin, *p*, which is passed through the clapper-bolt *x*, and the slot and pin *p* prevent the turning of the clapper, when the bell is rotated, so as to change the point of stroke of the clapper on the bell, the clapper being so pivoted to the bolt *x* as always to swing in a plane at right angles to the axis of the trunnions *t t*.

When it is desired to rotate the bell, so as to expose another part of it to the blows of the clapper,

all that is necessary is to slacken the bolts x a a' a'' , by loosening their nuts, when the bell may be readily turned, and it is fastened again by simply screwing up the nuts on their respective bolts.

It is manifest, that by our device, the yoke, instead of being at all weakened, as it would be if the crown of the bell passed into it, is materially strengthened by the support which it receives from the broad surface of the top of the crown-piece resting against and being bolted to it.

What we claim as our invention, and desire to secure by Letters Patent, is—

The annular flanged cavity in the crown-piece of the bell, around the central hole for the clapper-bolt, for the reception of the heads of the bolts by which the crown of the bell is attached to the yoke, and is thus rendered capable of being rotated, relatively to the yoke, substantially as hereinbefore described.

SAML. M. FULTON.
